UNITED STATES PATENT OFFICE.

GEORGE E. LEE, OF CLEVELAND, OHIO, ASSIGNEE TO THE GEORGE E. LEE COMPANY,
OF CLEVELAND, OHIO, A CORPORATION OF OHIO.

AUXILIARY MELTING DEVICE.

1,233,068.

Specification of Letters Patent. Patented July 10, 1917.

Application filed August 5, 1914. Serial No. 355,097.

To all whom it may concern:

Be it known that I, GEORGE E. LEE, a citizen of the United States, residing at Cleveland, in the county of Cuyahoga and State 5 of Ohio, have invented a certain new and useful Improvement in Auxiliary Melting Devices, of which the following is a full, clear, and exact description.

This invention relates to a device for replenishing molten material within a vessel 10 when the melted material within the vessel falls below a predetermined quantity.

Generally speaking, the invention comprises the elements and combinations there- 15 of, set forth in the accompanying claims.

Reference should be had to the accompanying drawings forming a part of this specification in which Figure 1 is a broken perspective view of the device forming the 20 subject matter of the invention, and Fig. 2 is a top plan view of certain portions of the device, and Fig. 3 is a vertical section through a portion of the device.

The device of this invention is primarily 25 intended for use in connection with a linotype machine, and is adapted to act in co-operation with the melting pot of such a machine, and is intended to supply molten type metal within the pot when the contents 30 thereof falls below a desired level. The device, while its description and its applica- 35 tion herein given refer particularly to a linotype machine, may be used in other connections and under other circumstances, and consequently, I do not limit myself in its application to a linotype machine.

In the drawings, the pot of a linotype machine is represented at 1, and as will be understood, the function of the melting pot 46 is to hold type metal in a molten condition and supply the molten metal to the mold of the machine at proper times.

Secured upon the frame of the linotype machine in any convenient position is a bracket 2. This bracket supports a post 3, which at its upper end carries a platform 4. The platform 4 is pivotally secured to the post 3, so that the platform 4 and the parts carried thereby may be swung away 50 from the melting pot when the same may be desirable or necessary. The platform 4 carries or has formed integrally therewith a housing 5, which as shown, is substantially circular. Within the housing 5 there is supported a burner 6. This burner is circular

in form and is provided with a neck 7 which has an opening extending through it.

Supported from the neck 7 is a Y shaped gas pipe 8, one portion of which is connected with a tube 9 that extends within the 60 housing 5 adjacent to burner and forms a pilot light. Another portion of the pipe 8 has a portion 10 which extends beneath the burner for a purpose which will be later described.

Extending from the post 3 is an arm 11, having thereon a short post 12. Upon this post 12 is secured a casing 13, provided with nipples 14 and 15. The nipple 14 co-operates with the opening in the neck 7 of the 70 burner, while the nipple 15 co-operates with the pipe 8. The nipple 14 is supplied with gas from any desired source, and the flow of gas through the nipple 14 is governed by any suitable regulating device, which operates in conjunction with the rise and fall of the molten material within the melting pot 1. 75

There are numerous such devices which are well known in the art, and no specific form of such a device is here given. In general these devices operate so that when the level of the molten material within the melting pot falls below a predetermined level, gas is admitted to the nipple 14, and when the molten material within the pot 1 shall 80 have reached the predetermined level, the passage of gas through the nipple 14 is discontinued. The passage of gas through the nipple 13 through the pipe 8 is substantially uniform so that the pilot light may be always lighted and the gas through the pipe 10 may also always be lighted.

The burner 6 may be of any desired shape, but the most convenient and practical form is substantially circular, in which form I 85 have shown it.

The burner is hollow and conducts the gas throughout the interior thereof. The inner wall of the burner is slanting, as indicated at 16, and is provided with a series of openings represented at 17. Upon the top of the burner are a series of tubes 18, which communicate with the interior of the burner and extend upwardly from the burner in a slanting direction. These tubes are provided 90 with openings indicated at 19. The interior wall 16 of the burner and the portions of the surfaces of the tubes provided with openings 19 lie in the same conical surface. The tubes 18 are preferably arranged in groups 110

as shown in the drawing, and permit a free flow of air between the tubes, and thus insure complete and proper combustion of the gas.

5 The housing 5 supports upon the interior thereof a melting cup 20. The upper portion of this cup is preferably substantially circular, while the lower portion as indicated at 21 is conical in shape. At the bottom the 10 conical portion 21 is truncated and forms an opening 22.

Upon the lower portion 21 of the melting cup there is pivotally secured a chute or guide 23. This chute is in position to receive material which may pass through the opening 22 and guide it into the melting pot 1. As will be seen from the drawing, the tube 10 is in position to direct a flame due to the burning of the gas at the end 20 of the tube 10 in a direction down and along chute 23, thus keeping the chute 23 in heated condition so that any molten metal passing from the cup 21 will not freeze in the chute 23.

25 Upon the housing 5 there is supported a substantially cylindrical protecting casing 24. This casing is formed at its lower end with a ring 25, to which ring are secured brackets 26. The brackets extend inwardly 30 and engage a ring member 27, which is of slightly less diameter than the interior of the cup 20. Extending upwardly from the ring 27 are guiding members 28. These members at their upper end are secured to a ring 29, and intermediate their ends are secured to a circular member 30, which circular member engages with the upper end of the protecting casing 24. The casing 24 is secured upon the platform 4 in any desired manner and is preferably removably secured.

The guiding members 28 are adapted to receive a cylindrical ingot of type metal, the diameter of which is such that it will easily 45 pass through the ring 27, so that the lower portion of the ingot will rest within the melting pot 20.

When heat is applied to the melting pot through the burner 6, the type metal of 50 ingot will be melted and run down the conical wall 21 of the melting cup under the chute 23, and thence drop into the melting pot 1. Gradually the ingot of metal will at its lower portion conform to the wall 21 55 of the melting cup, and therefore will be subjected substantially directly to the heating effect of the burner 6.

Obviously, additional ingots of type metal 60 may be placed one on top of the other with in the guide members 28, so that when the device has once started to operate, there will always be present within the melting cup 20 an ingot or portion of an ingot which will conform to the conical portion 21 of 65 the melting cup.

The melting cup 20 may be supported within the housing 5 in any desired manner, and for the purpose, I have shown legs, one of which is indicated at 30. These legs will serve to position the melting cup so 70 that the lowest conical portion thereof will extend centrally through the burner 6.

The inner face or wall 16 of the burner as well as the inclination of the tubes 18, is such that they extend substantially parallel 75 with the conical portion 21 of the melting cup; therefore, the flame produced by the burning of the gas at the burner 6 and the tubes 18, is directed substantially upon the entire conical surface 21 of the melting cup. 80

The burner 6 with its tubes 18 forms a particularly desirable type of burner for use in the connection shown and described. It is necessary to heat the entire conical surface 21 of the melting pot, but if a burner 85 of the usual ring type be used of sufficient height to cover the conical portion 21 of the top, it will be practically impossible for enough air to reach the burning gas to effect a complete combustion of the gas; consequently, considerable quantities of gas escape unconsumed, which is dangerous. But what is of more importance is that it is impossible under such conditions to secure 90 enough heat to effect the necessary and desired melting of the ingot of metal within the cup 20. By providing the ring 6 of limited extent with respect to the conical surface of the melting cup, and providing the upwardly extending tubes 18, the gas will 100 be entirely burned, for if all the gas is not burned on leaving the openings 17 of the burner 6, this gas will be subsequently burned, for as will be clear, air may find ready passage between the tubes 18, so that 105 when the gas unburned at the burner 6 reaches the vicinity of the tubes 18, it will be ignited and consumed.

As heretofore stated, the ring 27 is of slightly less diameter than the diameter of 110 the cup 20, and keeps the ingot from contacting with the upper edge of the cup 20, so that there is no danger of the ingot melting at this point and running down upon the outside of the cup. 115

The particular shape which is given to the melting cup, that is to say, providing the lower portion as a conical surface, prevents 120 the collection of any dross within the cup. The melted metal and any dross present will pass through the conical bottom portion 21, each succeeding ingot as it descends into the cup and forms itself to fit the conical portion of the melting cup, scrapes the wall of 125 the cup and forces any dross and dirt which may perchance have adhered to the wall, down and out of the opening 22. Consequently, whatever dross there may be will 130

collect in the melting pot 1, from which it may be skimmed.

The member 31 is provided with a rounding surface, and when the platform 4 is 5 swung, to move the feeder away from the melting pot, the member 31 engages the edge of pot and due to the rounding of member 31, the chute is elevated and so passes over the edge of the pot.

10 Details of construction may be altered in the device herein shown without departing from the spirit of my invention.

Having described my invention my claim is:-

15 1. In a device of the character described, the combination with a receptacle adapted to contain melted material, of a melting cup above said receptacle and adapted to receive material to be melted in solid form, 20 the lower portion of said cup being formed with converging sides, and a heating device directly coöperating with the converging portion of the melting cup and applying heat to the cup directly and substantially 25 only to the converging portion thereof.

2. In a device of the character described, the combination with a receptacle adapted to contain melted material, of a melting cup above said receptacle and adapted to receive 30 material to be melted in solid form, the lower portion of said cup being formed with converging sides and an opening at the lower portion of the converging sides, a heating device surrounding the converging 35 sides of the melting cup and extending along said converging portion to apply heat to the melting cup substantially only at the converging side portion.

3. In a device of the character described, 40 the combination with a receptacle adapted to contain material in melted form, of a melting cup supported above the receptacle and adapted to contain material to be melted in solid form, the lower portion of said cup 45 being provided with converging sides and an opening at the lower portion of the converging sides and a burner surrounding the lower portion of the melting cup and directing its flame against the converging portion of the 50 melting cup.

4. In a device of the character described, the combination with a receptacle adapted to contain material in melted form of a melting cup mounted above said receptacle said 55 melting cup having the lower portion thereof formed with converging sides and an opening at the lower portion of the converging sides, an ingot of metal within said cup and having the end thereof conforming with 60 the converging sides of the melting cup, and a heating device directly coöperating with the converging portion of the melting cup

and applying heat to the cup directly and substantially only to the converging portion thereof.

65

5. In a device of the character described, the combination with a receptacle adapted to contain material in melted form of a melting cup mounted above said receptacle said melting cup being conically shaped at its 70 lower end and having a small unobstructed opening at the lower end of the conical portion, a metal ingot within said cup the lower portion of said ingot conforming with the conical portion of the cup, and a heating 75 device directly coöperating with the conical portion of the melting cup and applying heat to the cup directly and substantially only to the converging portion thereof.

6. In a device of the character described, 80 the combination with a receptacle adapted to contain material in melted form of a melting cup mounted above said receptacle said cup being conically shaped at the lower portion thereof and having a small unob- 85 structed opening at the lower end of the conical portion, a metal ingot extending within the said cup said ingot at the lower portion thereof conforming with the conical portion of the cup, and a burner surround- 90 ing the conical portion of the cup whereby the flame from the burner is directed against the conical portion of the cup.

7. In a device of the character described, 95 the combination with a receptacle adapted to contain material in melted form, of a melting cup supported above the receptacle, said cup being provided with an opening in the lower portion thereof, a chute extending beneath the said opening and also extending 100 at an angle into the receptacle whereby material from the melting cup will be transported to the receptacle and discharged at an angle with respect to the surface of the material therein, and means for heating the 105 melting cup.

8. In a device of the character described, the combination with a receptacle adapted to contain material in melted form, of a melting cup supported above the receptacle and 110 adapted to contain the material to be melted in solid form, said cup being provided with an opening at the lower portion, a chute coöperating with the opening in the melting cup and extending into the receptacle to 115 guide material from the melting cup to the receptacle, means for heating the melting cup, and means for heating the chute.

In testimony whereof, I hereunto affix my signature in the presence of two witnesses.

GEORGE E. LEE.
